Corporation of America, a corporation of Dela-
ware

Application August 5, 1938, Serial No. 223,148
In Great Britain August 25, 1937

2 Claims. (Cl. 178—7.3)

This invention relates to television receivers and more particularly to anti-fading automatic volume control (A. V. C. systems) therefor.

The use of A. V. C. systems is now common practice in broadcast radio receivers for sound programmes. Although the provision of an A. V. C. system is highly desirable in a television receiver just as in a sound programme receiver, if it be sought to apply an ordinary A. V. C. system as well known in broadcast sound programme receiver practice, to a television receiver, there arises a serious defect which is not at first sight obvious. In such an ordinary A. V. C. system the gain control is effected by rectifying the incoming carrier to derive the gain controlling potentials, i. e. such an A. V. C. system operates on the general incoming carrier level. In modern television systems, however, the general carrier level as transmitted is not constant but is varied in accordance with background or average picture brightness. If therefore an ordinary A. V. C. system of the type usual in broadcast sound programme receivers is applied to a television receiver it will operate not only to compensate for fading variations (as is desired) but also to destroy desired variations corresponding to average picture brightness variations. The main object of this invention is to avoid this defect.

According to this invention a television receiver is provided with an A. V. C. system which is responsive not to variations in general incoming carrier level but to variations in a predetermined selected signal component which, as transmitted, is of substantially constant level. A signal component available for selection and which is transmitted at a substantially constant level in most present day television transmitters is provided by the synchronizing pulses (either the line synchronizing or the framing synchronizing pulses, or both) these pulses being usually maintained, as transmitted, at about 30% of the peak value of the carrier, as transmitted. In carrying out this invention the selected signal component, after separation at the receiver, is utilized to provide a gain controlling uni-directional potential which is employed in any known convenient way, e. g. as gain controlling grid bias, to control the gain of a carrier stage or stages of the receiver.

The invention is illustrated in and further explained in connection with the accompanying graphical and diagrammatic drawing which relates to one way of carrying out the invention.

Figure 1 shows a composite picture and syn-

chronizing signal such as developed in the final detector of a receiving device.

Figure 2 shows the controlling wave form and the wave forms developed by the A. V. C. device of Figure 3.

Figure 3 is a diagram of the circuit of the A. V. C. device.

Referring to the drawing, synchronizing signals are separated out by any known apparatus (not shown) from the total signals received and then, if required, amplified. The nature of the received signals received from a transmitter which transmits signals including a D. C. component representative of general picture brightness is represented conventionally in Figure 1. Here three scan lines are represented at I, II, and III. I is a "dull illumination" picture line which has been subjected to fading; II is the same line without fading; and III is a "bright illumination" picture line. The broken line represents the carrier cut-off point. The result of separation out of the synchronizing signals will be, as shown conventionally at a in Figure 2, a series of unidirectional pulses of a polarity which will depend upon the method of selection employed and of an amplitude which will be (in the absence of fading) constant. It is arranged that these pulses are in the positive direction as shown in Figure 2 at a. Since these pulses will be of relatively short duration as compared to the intervals between them, direct rectification and smoothing to produce the actual gain controlling potential is not easy and it is therefore much to be preferred to precede rectification by a wave shape transforming operation which changes the pulse wave form into a form more convenient for rectification. One way of doing this is shown in Figure 3. Here the pulses are applied, for example through a coupling condenser 1, to the grid 2 of a valve 3, e. g. a triode whose anode-cathode circuit includes a condenser 4 and whose anode receives positive potential through a resistance 5. The cathode leg contains the usual capacity shunted self-bias resistance combination 6, 7, and the grid receives cut-off bias through a grid resistance 8. The arrangement is such that during each interval between pulses the condenser 4 charges up through the resistance 5, the rate and law of charging depending upon the value of this resistance 5, the value of this potential and the size of the condenser 4. Rectilinearity of charging is not an important desideratum and the preferred arrangement is that in which the condenser 4 becomes charged substantially to the

anode voltage in a period slightly less than the period between successive pulses. When a pulse is applied to the grid 2 the valve, which was previously biased to cut-off, becomes conductive and the condenser 4 partially discharges rapidly through the valve. Accordingly, there will be set up across the condenser 4 a voltage wave form of modified saw-tooth shape as shown at *b* in Figure 2, the sawtooth having flattened tops. If fading occurs and the pulses accordingly become of less amplitude there will obviously be a less complete discharge of the condenser 4 at each pulse and the output wave form will be, as shown at *c* in Figure 2, of reduced amplitude with longer flat tops to the sawtooth. Such a modified sawtooth wave form is quite convenient for rectification. For example, and again as shown in Figure 3, this wave form may be applied through a coupling condenser 9 to a rectifier 10 and whose output, after smoothing in the usual way, is applied via lead 11 as gain controlling bias to the grid or grids of a variable- μ carrier amplifier valve or valves (not shown) in the receiver. Obviously, any convenient form of rectifier may be used; for example, if a double diode is used the said double diode may be constituted by the diode section of a double-diode triode, the triode section of which constitutes the valve 3.

Either the line or the frame synchronizing signals may be selected and utilized for the purposes of this invention. Selection of the line signals presents the advantage of involving less elaborate smoothing (since the line frequency is much higher than the frame frequency) but selection of the frame signals offers the advantage of ease of separation.

What we claim is:

1. In an automatic volume control system for radiant energy receivers wherein recurrent signals of a predetermined amplitude are transmitted, a thermionic vacuum tube having anode, cathode and at least one control electrode, means for impressing said recurrent wave onto a control electrode of said thermionic tube, means for storing energy connected in the anode-cathode path of said tube, means for storing energy in said energy storage means during intervals when said tube is in a non-conductive state, and discharging said energy when the wave form impressed onto the control electrode of said tube renders the tube conducting, said discharge being caused by said signals and proportional to the amplitude thereof, thus forming a serrated wave form, means for rectifying said wave form to develop a control potential, and means to utilize said control potential for automatic volume control purposes.
2. In a television receiver wherein signals of predetermined amplitude are received intermittently, indicating the level of the transmitted carrier, the method of developing automatic-volume-control signals which comprises the steps of storing electrical energy, discharging said energy by said signals, and controlling the amount of discharge by the amplitude of said signals, rectifying said stored energy and utilizing the rectified energy for automatic-volume-control purposes.
